US00D844441S

(12) **United States Design Patent** (10) **Patent No.:** **US D844,441 S**
DeMarco et al. (45) **Date of Patent:** **** Apr. 2, 2019**

(54) **COSMETIC CONTAINER**

- (71) Applicant: **Mary Kay Inc.**, Addison, TX (US)
(72) Inventors: **Jenny DeMarco**, Frisco, TX (US);
Tammy Schriewer, Addison, TX (US)
(73) Assignee: **Mary Kay Inc.**, Addison, TX (US)

(**) Term: **15 Years**(21) Appl. No.: **29/610,191**(22) Filed: **Jul. 10, 2017****Related U.S. Application Data**

- (60) Continuation of application No. 29/537,050, filed on Aug. 21, 2015, now Pat. No. Des. 795,075, which is a division of application No. 29/502,064, filed on Sep. 11, 2014, now Pat. No. Des. 739,739.
